DRAFTSMAN'S TABLE

Filed March 29, 1930

UNITED STATES PATENT OFFICE

CARL F. CLAUSEN, OF GRAYSLAKE, ILLINOIS

DRAFTSMAN'S TABLE

Application filed March 29, 1930. Serial No. 440,135.

My invention relates to improvements in draftsmen's tables, and it consists in the combinations, constructions, and arrangements herein described and claimed.

An object of my invention is to provide a draftsman's table which is intended primarily for use in tracing, but which may be used for ordinary drafting purposes as well, and in which details, such as fine lines, may be readily located and traced, owing to the novel arrangement of lights underneath the surface upon which the drawing is made.

A further object of the invention is to provide a draftsman's table which is illuminated by electric lights placed underneath the drawing surface, and in which special provision is made for ventilating the under side of the drawing surface so as to prevent undue heating thereof.

A further object is to provide a drawing table having a transparent drawing surface in which means is provided for permitting the needle points of the drawing instruments to enter a sufficient distance to permit the effective use of the instruments, but which will not permit them to enter too far, thereby obviating the danger of making large holes in the drawing.

A further object is to provide a device of the type described in which the light from the lamps is evenly distributed, thus obviating the danger of glare and shadows.

A further object is to provide a draftsman's table partly of wood and partly of metal in which the top may be readily removed or replaced to have access to the lamps.

Other objects and advantages will appear in the following specification, and the novel features of the invention will be particularly pointed out in the appended claims.

My invention is illustrated in the accompanying drawing, forming part of this application, in which

Figure 1 is a plan view of the device, certain parts being shown in section,

Figure 2 is an enlarged sectional detail view of a portion of the device, the section being taken along the line 2-2 of Figure 1, 50

Figure 3 is a sectional detail view along the line 3-3 of Figure 2, and

Figure 4 is a sectional detail view along the line 4-4 of Figure 3.

In carrying out my invention I provide 55 a central support 1 having a series of sockets 2 for incandescent lamps 3. This central support 1 in reality forms the bottom of a tray, the sides consisting of metal portions 4 which are inclined upwardly and outwardly and have at their extremities integral vertically extending portions 5. The portions 5 are bent outwardly at their tops and then downwardly to provide flanges 6.

Ventilating openings or slots 7 are provided in the member 1 as shown in Figures 1 and 2, while ventilating slots 8 are provided in the vertically extending portions 5.

Secured to the inclined portion 4 are legs or brackets 9 which support at their top a baffle 70 plate 10. The latter may be made of heat-resisting material such as transparent or translucent glass which will permit the passage of light, but will shield the drawing surface from heat, as hereinafter explained.

Legs 11 are provided, the upper portions of these legs entering between the members 5 and 6 and being secured in position by means of bolts such as that shown at 12. At 13, I have shown a series of rectangular lugs, these 80 lugs being secured to the metal portions by means of screws, such as that shown at 14, see Figure 4, and being spaced symmetrically.

The top consists of a rectangular wooden frame 15 having a groove 16 arranged to receive a plate of glass 17. Surmounting this glass plate is a transparent sheet of celluloid 18 which, as shown in the drawing, is of a thickness to come flush with the upper surface of the frame member 15 so as to provide an 85 90 95

unobstructed drawing surface. The frame member 15, as will be seen from the drawing, extends beyond the legs 11. To the under side of the frame member 15 are secured lugs 19 having a recess arranged to receive the lugs 13. 5 The lugs 19 may be secured to the frame in any suitable manner as by means of screws 20, see Figure 4.

From the foregoing description of the various parts of the device, the operation thereof 10 may be readily understood. With the device as assembled and the lamps connected with any suitable source of current supply, not shown, the light is partially reflected by the baffle plate 10 and is reflected by the metal 15 surfaces 4 and 5 so as to illuminate the drawing surface. The wooden frame 15 will receive thumb tacks for holding the drawing paper or tracing cloth in position, and the light coming through the drawing surface 20 will show up details such as fine lines.

The heat from the lamps is shielded by the plate 10 and is carried by the convection currents entering the openings 7 and passing out through the openings 8. At the same time the drawing surface is sufficiently heated to cause the ink to dry in a short time. The provision 25 of the celluloid sheet as stated gives a good anchorage for the needle point of the drawing instrument, preventing the drawings from 30 being mutilated by large holes.

When it is desired to replace or remove the lamps, the top may be lifted upwardly and 35 may be replaced after the lamps have been removed or replaced since the lugs 19 form 40 guide means for the lugs 13 so that the top is easily brought to the initial position.

I claim:

1. A tracing table of the class described, 40 said tracing table including a supported diaphanous flat top portion, said top portion comprising a relatively rigid diaphanous plate having a tough resilient diaphanous layer superimposed on the upper surface 45 thereof for receiving pointed instruments whereby a sheet of paper may be secured on the upper surface of said top portion, said table being provided with a depending lamp supporting member extending underneath 50 said glass plate, and a diaphanous heat deflecting member secured to said lamp supporting member, said heat deflecting member and said plate being spaced apart from each other for permitting air to move between the plate 55 and the heat deflecting member.

2. A tracing table of the class described, 60 said tracing table including a supported diaphanous flat top portion, said top portion comprising a relatively rigid diaphanous plate having a tough resilient diaphanous layer superimposed on the upper surface 65 thereof for receiving pointed instruments whereby a sheet of paper may be secured on the upper surface of said top portion, said plate being made of vitreous material, said

layer consisting of a sheet of celluloid contacting the upper surface of the plate, said table being provided with a depending lamp supporting member extending underneath 70 said glass plate, and a diaphanous heat deflecting member secured to said lamp supporting member, said heat deflecting member and said plate being spaced apart from each other for permitting air to move between the plate 75 and the heat deflecting member.

Signed at Libertyville in the county of Lake and State of Illinois this 22 day of March A. D. 1930.

CARL F. CLAUSEN.
